(57) **CLAIM**

We claim the ornamental design for a cargo securing apparatus, as shown and described.

DESCRIPTION

FIG. 1 is a top perspective view of a cargo securing apparatus design;

FIG. 2 is a bottom perspective view thereof;

FIG. 3 is a front elevation view thereof;

FIG. 4 is a rear elevation view thereof;

FIG. 5 is a right side elevation view of the cargo securing apparatus, the left side being a mirror image thereof;

FIG. 6 is a top plan view of the cargo securing apparatus; and,

FIG. 7 is a bottom plan view thereof.

Portions of the drawings shown in broken lines illustrate environmental structure and form no part of the claimed design.
